UNITED STATES PATENT OFFICE.

JOSEPH S. WOOD, OF BROOKLYN, NEW YORK, ASSIGNOR OF ONE-HALF HIS
RIGHT TO JOHN J. CARBERRY, OF PHILADELPHIA, PENNSYLVANIA.

IMPROVEMENT IN GAS-GENERATORS.

Specification forming part of Letters Patent No. 138,778, dated May 13, 1873; application filed
March 25, 1873.

To all whom it may concern:

Be it known that I, JOSEPH S. WOOD, of 66 Tillary street, Brooklyn, New York, have invented certain Improvements in Generating Hydrogen and Hydrocarbon Gas, of which the following is a specification:

This invention is an improvement on my patents of April 5, 1870 and July 26, 1870; the same general principle of construction is maintained, but with a superior arrangement and combination of the parts, making the machine simpler and much safer.

The nature of my invention consists in the construction and arrangement of an apparatus having a dilute-acid chamber and a lower gas-generating chamber. The latter has a perforated false bottom for the iron turnings to rest on, and arranged therewith and inside of the gas-generator is a circulating-pipe controlled by a plug or valve, which plug, when removed, permits the dilute acid to circulate from one chamber to the other according to the pressure of the gas. This rising and falling of the dilute acid upon the iron filings used to make the hydrogen regulates automatically the quantity of gas made.

Figure 1 is an elevation of my machine, showing one of the gas-generators and the carbureter in section.

A is a cylindrical wooden vessel having a partition, a' , across the middle, so as to divide it into an upper chamber, B, and a lower chamber, C. Near the bottom of the lower chamber is a perforated plate or false bottom, c' , upon which the iron turnings are placed. These are inserted into the compartment by removing the water-tight screw-plug d , after which the plug is secured firmly in its place. A pipe, E, connects the upper chamber B with the lower one C. This pipe has its lower outlet below the level of the plate c' . The upper end opens into the acid-chamber B, and is closed by a wooden plug, g , the stem of which rises to the top of the tank B and above the surface of the dilute acid contained therein. This plug or valve g is used while filling the machine, as it enables the operator to judge more accurately of the quantity of liquid required, and affords the opportunity to test the gravity of

the liquid. When the machine is charged the plug is withdrawn and carried away as a matter of safety to prevent the pipe E being stopped up. The pipe h is the outlet for hydrogen gas to the carbureter K. The gas, passing to the bottom of the vessel K, bubbles up through the hydrocarbon liquid and passes off as carbureted hydrogen by the pipe L to the gas-burner. S is the inlet for hydrocarbon, closed by a screw-plug.

It is not essential that the pipe h should pass up through the chamber B. By raising it, however, considerably above the chamber C the dilute acid is prevented from being forced over into the carbureter K.

The vessel A is open to the air at the top, but covered with a lid, M, removable, so that the tank B can be filled with water and acid, and its temperature and density easily tested.

Two machines, A, are connected by stop-cocks p to one carbureter, so that one machine can be filled while the other is in use. The refuse liquid is drawn off by the cock R.

The machine operates in this manner: The carbureter having been disconnected from the gas-generator by a suitable union in the pipe n , the lid M is removed, the plug g inserted in the pipe, and the chamber C is filled with iron-turnings and the plug d is securely fastened. The upper tank B is then filled with dilute sulphuric acid and the plug g removed. The dilute acid runs down the pipe E and fills the lower chamber, and hydrogen is at once formed, forcing out the air first; then, as soon as the carbureter is connected to the gas-generator and the pressure of gas is sufficient, the dilute acid is forced again up into the tank B. As the liquid falls in the tank C less gas is made, and the quantity is thus regulated according to the outflow through the pipe h to the carbureter and gas-burners. As soon as the liquid is forced below the plate c' no more gas is made, and as the pipe E projects below the plate c' the liquid always remains as a seal at its lower end, preventing the exit of hydrogen up the pipe E.

I do not claim, broadly, in this patent the communicating passage controlled by a cock or valve between the acid and gas chambers

for equalizing the pressure of the gas, as that is claimed in my patent of April 5, 1870.

I claim—

1. The perforated false bottom c' , in combination with a communicating passage, E, for the circulation of dilute acid controlled by a plug or valve, g , the said passage having its lower termination at or below the said false bottom of the generating-chamber and the other end terminating in the acid-chamber, as herein described.

2. The circulating-pipe E having its lower termination below the level of the iron-turnings contained in the gas-generating chamber and the other termination in the dilute-acid chamber, and controlled by a plug or valve therein, substantially as herein described.

JOSEPH S. WOOD.
